KNITTING MACHINE

Ivan W. Grothey, Laconia, N. H., assignor to
 Scott & Williams, Incorporated, New York,
 N. Y., a corporation of Massachusetts

Application April 28, 1933, Serial No. 668,456

14 Claims. (Cl. 66—50)

This invention relates to knitting machines and more particularly to circular knitting machines arranged to wrap comparatively small groups of selected needles with embroidery yarns in order to form embroidery patterns of various designs and it is an object of this invention to provide an improved knitting machine of the type described which normally knits a plurality of yarns in plating relation in order to form the fabric and which knits embroidery yarns with the backing yarn, while the normal facing yarn is floated in order to form embroidery patterns. It is also an object of this invention to provide a knitting machine of the type described, by which hollow or open embroidery patterns are formed by knitting embroidery yarns with the backing yarn while the normal facing yarn floats and normally plated fabric or normally plated fabric and patterns of the backing yarn alone are formed within the outline of the hollow or open embroidery pattern, the embroidery yarns and the normal facing yarn being floated between the wales of the embroidery pattern in which they are fed to the needles.

In the drawings, in which this invention is shown applied to a Scott and Williams circular knitting machine of the general type shown in the patent to Page and Swinglehurst, No. 1,906,204, issued April 25, 1933. The wrap mechanism broadly is claimed in the application of William N. Taggart, Ser. No. 560,153, filed August 29, 1931.

Fig. 1 is a horizontal section of the head of a circular knitting machine constructed in accordance with this invention, the section being taken above the operating cams for the jacks, and some parts being broken away to show other parts more clearly;

Fig. 2 is a partial horizontal section of the machine shown in Fig. 1 drawn to a larger scale and taken on a lower plane than Fig. 1; a number of parts being omitted in order to more clearly show various positions of the jacks, a particular group of jacks being indicated in several successive positions;

Fig. 3 is a view in elevation of the means limiting the inward movement of the reeder cams used in the jack selecting means;

Fig. 4 is a view in elevation of a modification of the structure shown in Fig. 3;

Fig. 5 is a plan view of the structure shown in Fig. 4;

Fig. 6 is a partial vertical section taken on line 6—6 of Fig. 1 and showing a detail of the

means for rendering the jack selection means operative or inoperative;

Figs. 7, 8, 9, and 10 are vertical sections through the needle cylinder taken at different places so as to show different phases of the jack and needle operation; Fig. 7 showing jack selection between jacks of embroidery and plating needles; Fig. 8 showing embroidery needles raised by their jacks for operation by needle operating cams to take the embroidery yarn; Fig. 9 showing an embroidery needle taking the embroidery yarn, its auxiliary jack lowering its main jack and a cam operating the lower portion of the main jack inwardly; Fig. 10 showing the operation of the jacks of the plating needles to press their lower portions outwardly in position for operation by their operating cam; and

Fig. 11 is a development of a portion of the needle cylinder with the operating cams for the needles and jacks positioned thereon and showing successive phases in the operation of a group of needles which may take the same embroidery yarn and their jacks in a single rotation of the needle cylinder.

In the drawings there have been shown only such parts of the knitting machine shown in the Page and Swinglehurst Patent No. 1,906,204, as are necessary for an understanding of this invention and its relation to the knitting machine of said patent as the various parts of the knitting machine shown are operated in the same manner as in said Patent No. 1,906,204, except where a modified construction and operation are herein set forth.

As shown in the drawings the machine comprises a revolving needle cylinder 260 operated by suitable operating means (not shown) which may be as shown in the patent to Robert W. Scott, No. 1,152,850, issued September 7, 1915. The revolving needle cylinder contains a circular series of vertically movable independent needles N, which cooperate with the usual knitting cams 357, 360, 361 located below the throat plate 560 in the usual latch ring. The usual sinkers and sinker cam cap will also be provided, as will also the pattern yarn bobbin stand, its operating means and the pattern yarn fingers as shown in Patent No. 1,906,204.

Cooperating with the knitting cams in the operating of the needles are jacks 736 lying in the slots of the needle cylinder 260 below the needles N and operated by cams, to be later described, which are mounted on the bed plate B to raise selected needles to receive the wrapping and facing yarns. The selection of the jacks for the

55

operation of the needles is accomplished as in Patent No. 1,906,204, by means of a trick wheel 800 rotatably mounted on the bed plate B and which is racked a step at a time by the ratchet pawl 803 in the usual manner. The trick wheel 800 has vertical slots in which are mounted pattern jacks having a plurality of butts thereon. Various butts on the pattern jacks are broken off in accordance with the desired pattern, so that the pattern jacks will cooperate with reader cams 820 pivotally mounted one above another on the vertical post 821 mounted in the bed plate B. The reader cams 820 select the jacks 736 for operation by the operating cams and the jacks control the operation of the needles to receive the various yarns.

Pattern yarn finger selecting mechanism as shown in Patent No. 1,906,204 is also provided. This comprises the reader cams 825 and 825' which are connected to the yarn finger selector cam (not shown) by the links 834 and 834', shaft 832 and sleeve 833 and lever arms 838 and 839.

Cooperating with the two lower butts of the pattern jacks of the trick wheel 800 are reader cams 820a and 820b, shown in the drawings, as the two lowermost reader cams on the vertical post 821. The reader cams 820a and 820b have cam portions which engage butts on the jacks 736 and forked ends 822a and 822b similar to the forked end 822 of the cams 820 which engage a stop 99 to limit the movement of the reader cams toward the jacks. The stop 99 may be a separately adjustable lower portion of the usual reader cam stop positioned so as to limit the cams 820a and 820b to a lesser inward movement than cams 820. In Fig. 3, the stop 99 is shown of sufficient height to cooperate with a number of reader cams. In the modification shown in Figs. 4 and 5, the stop 99' is additional to the usual reader cam stop and is placed so as to limit the reader cams it engages to a lesser inward movement than the usual reader cam stop. The stop 99' may be of sufficient height to engage a greater number of reader cams than the two reader cams 820a and 820b with which it is shown cooperating in the drawings. Jacks having butts engaged by the reader cams 820a and 820b have their bottom portions moved inwardly to a less extent than jacks having butts engaged by the reader cams 820.

In order to insure engagement of the jacks by the reader cams 820, 820a and 820b, there is placed in advance of the reader cams a cam 100 which is pivotally mounted upon the upper portion of the post 821 in position to engage butts 736a at the upper portions of the jacks and move the upper portions of the jacks inwardly and the lower portions outwardly, the jacks, as shown in Figs. 7 to 10, being slightly angular. The cam 100 is provided with an operating arm 101 extending at an angle to the body of the cam 100 and positioned to be engaged and operated by the stepped end of a push rod 103, which is operated by cams on the main pattern drum (not shown) and is guided in a slot in a guide bracket 104 attached to the bed plate B. A spring 105 attached to the arm 101 and the bed plate B holds the arm 101 in engagement with the stepped end of the push rod 103 and retracts the arm 101 to withdraw the cam 100 from operative position as the push rod 103 is withdrawn or lowered.

Pivots mounted on a post 106 carried by the bedplate B is one end of a lever 107, the op-

posite end of which is connected to the arm 101 by the link 108. Upon the lever 107 intermediate the ends thereof there is mounted a cam 110 positioned to engage butts at the upper portions of some of the jacks. The connection between the arm 101 and lever 107 is such that the cams 100 and 110 are moved similarly and simultaneously, that is, they are moved towards the jacks simultaneously and away from the jacks simultaneously. As shown in Fig. 11, cam 10 110 is situated in substantially the same plane as the cam 100 and is positioned to engage the top butts of all jacks which are in their lowest position.

Attached to the bedplate B are cams 113, 114, 15 115 and 120, cam 113 affording an outer cam face or surface 116 spaced from the needle cylinder sufficiently so as to be engaged only by those jacks which have not been pushed in by any of the reader cams, and an inner cam face 20 or surface 117 positioned so as to be engaged only by those jacks which are forced part way in by either reader cam 820a or 820b. Those jacks which are moved all the way in by any of the reader cams 820 do not contact with 25 either cam surface 116 or 117 of the cam 113. Cam 114 is positioned to engage all jacks, the lower portions of which have not been moved inwardly to the fullest extent and moves the lower ends thereof inwardly to the maximum 30 amount so that the butts on the upper ends of all jacks which have not been raised will be positioned to be engaged by the cam 110 which moves the upper ends of such jacks inwardly and the lower ends thereof outwardly in position to 35 be engaged by the cam surface 118 of the cam 115. Following the cam 115 is a cam 120 which engages the bottom butts of all the jacks so as to move the bottom portions of all the jacks inwardly, which position is retained by the jacks 40 until engaged by the cam 100.

In the operation of the machine the trick wheel 800 is racked forward by the pawl 803 bringing the various pattern jacks into register with the reader cams 820 and operating the 45 reader cams in accordance therewith. With the operation of the upper reader cams 820 those jacks having butts engaged by the reader cams 820 have their bottom portions moved inwardly so that the jacks will not be engaged and raised 50 by the cam 113 while the jacks which do not have butts engaged by the upper reader cams have their bottom portions left in the outer or forward position to be engaged by the cam 113. This arrangement divides the needles into two 55 groups, one group comprising needles whose jacks are not engaged by the cam 113 and which are subsequently operated to take both the facing and backing yarns and the other group comprising needles whose jacks are raised by the 60 cam 113 and which needles do not take the facing yarn but do take the backing yarn and may or may not be raised to take the wrapping yarn. With the operation of the two lower reader cams 820a and 820b which have a lesser inward 65 movement than reader cams 820, those of the jacks not engaged by the upper reader cams 820 and which have butts engaged by either of the lower reader cams, will be moved inwardly at the bottom sufficiently to clear the face 116 70 of cam 113 but not far enough to clear the face 117 of cam 113. The jacks not pushed in by any of the reader cams 820, 820a or 820b are left with their bottom portions in the outer or forward position where they are engaged by the 75

face 116 of cam 113. The provision of reader cams 820a and 820b provides an additional selection among the needles which do not take the facing yarn which permits of such needles being operated to take both the wrapping and backing yarns or the backing yarn alone as all needles whose jacks are not moved inwardly by reader cams 820 are operated to take both wrapping and backing yarns unless their jacks are moved inwardly part way by the reader cams 820a and 820b in which case these needles take the backing yarn only. Providing the two reader cams 820a and 820b for this additional selection makes possible a two-step pattern but it is to be understood the patterns of a greater number of steps can be provided by the use of a larger number of reader cams having the same limited inward movement as reader cams 820a and 820b. For the purpose of more clearly illustrating the operations above described the jacks which are moved inwardly by the reader cams 820 are shown in outline in Fig. 11; the jacks which are moved inwardly part way by reader cams 820a and 820b are shown stippled, while the jacks which are not operated by any of the reader cams 820, 820a and 820b, are shown in black. The needles corresponding to these jacks are similarly drawn.

The jacks whose lower portions have been moved all the way in by the reader cams 820 will not be raised by the cam 113; the jacks which have been moved part way in by the reader cams 820a and 820b will be raised by the cam surface 117 to a point in which the large butts 736a at the upper ends of the jacks are above the level of the cam 110 and while these jacks operate the intermediate jacks their operation has no effect upon the needles in the same grooves. The jacks which are not moved inwardly by the reader cams 820a and 820b are raised by the cam surface 116 to the full height of the cam 113, moving the intermediate jacks in the same grooves therewith into engagement with the needles N in the same grooves and raising the needles to a position in which they will be operated by the cam 125 to a position in which the needles take the embroidery or wrapping yarn F² from the corresponding wrapping yarn guide as shown in Fig. 11. As the jacks raise the needles into position to engage the cam 125 they pass from the cam 113 and butts on the lower ends of the intermediate jacks, engage the cam 128 and draw down the jacks of the needles taking the wrapping yarns to the level of the jacks which were raised by the inner cam face 117 of the cam 113. As the jacks pass off the cam 113 they approach the cam 114 positioned to engage all jacks and move inwardly the lower ends of all jacks which have not been moved inwardly the full distance. Moving the lower ends of the jacks inwardly forces the upper ends of the jacks outwardly and the butts 736a on the upper ends of the jacks which have not been raised are engaged by the cam 110 as shown in Fig. 10, while the corresponding butts on the other jacks pass above the cam 110 and these jacks are not operated by cam 110. The jacks engaged by the cams 110 have the lower ends moved outwardly to engage with the cam 118, while the remaining jacks pass in front of the cam and are not operated thereby.

The needles to which the wrapping yarns are fed are engaged by the cam 126 and lowered to a level in which they will receive the backing yarn

F¹ at the throat plate 560, but not the facing yarn F², while the needles corresponding to the jacks raised by the cam face 117 have not been operated by the jacks but are left by the draw down cam 90 at such a level that they take only 5 the body yarn F¹ at the throat plate. The jacks which engage the cam face 118 of the cam 115 are raised to elevate the corresponding needles to a position in which both the facing and backing yarns F² and F¹ respectively are 10 taken at the throat plate 560 and these needles, as well as the remaining needles, are operated to knit by the usual knitting cams 357 and 360 at the throat plate. As the jacks operated by the cam 115 raise the needles to take the facing yarn F², they pass from the cam 115 and the butts on the lower ends of the intermediate jacks are engaged by the cam 130 which also engages the corresponding butts on all of the other intermediate jacks, so that all jacks are 20 lowered to a position in which the butts at the lower ends thereof are engaged by the cam 120 and the butts at the upper ends of the jacks positioned for engagement by the cam 100.

After operation by the regular knitting cams 25 the needles are raised by the clearing cam 80 and lowered by the draw down cam 90 so that the loops on all needles are cleared of the latches and the needles are returned to a position in which the loops are below the latches and the 30 needles are at the proper level for taking the backing yarn F¹.

In the operation of this machine it will be noted that the selection made by the upper reader cams 820 between wrapping and non-wrapping needles or between needles which knit and needles which float the normal facing yarn F² determines the width; that is, the number of wales in an embroidery pattern in any particular course. The jacks of the needles selected for 35 wrapping by the upper reader cams 820 are left with their lower ends pressed out in position to have their bottom butts engaged by the two lower reader cams 820a and 820b operated by the trick wheel 800. This renders it possible 40 to make a further selection of needles which do not take the wrapping yarn among the needles selected by the upper reader cams 820 for taking the wrapping yarn and floating the normal facing yarn and it is thus possible to make selections such that normally plated fabric and patterns of the backing yarn alone may be knit within the limits, that is, between wales of an embroidery pattern. It also makes possible the 45 knitting of patterns of the body yarn only by 50 moving in part way by reader cams 820a and 820b the jacks of a group of needles so as to float the normal plating yarn on these needles.

A fabric of the type knit on the machine above described is shown and described in my 60 co-pending application Serial No. 668,457, filed April 28, 1933.

What is claimed is:—

1. In a knitting machine, yarn guides supplying a plurality of yarns, needles for selectively 65 knitting said yarns, cams operating said needles to take and knit said yarns, jacks positioning needles for selective operation by said cams, jack selecting means, means operating a plurality of jack selections to different levels for determining 70 the selection of yarns by the needles of said jacks, means operating the remaining jack selections and means maintaining the jack selections until all jacks are operated.

2. In a knitting machine having independent 75

- needles yarn guides for supplying wrapping, facing and backing yarns to said needles, cams for operating said needles to take said yarns, jacks for effecting selective operation of said needles by said cams, jack selecting means, cam means acting on selected jacks to cause needles to be raised for wrapping and to raise the jacks of the needles taking the backing yarn only, said jack selecting means causing the remaining jacks to pass said jack operating cam means, a cam to operate the remaining jacks to raise their needles for plating, means positioning the jacks of the plating needles for operation by said cam means and means positioning the jacks of the needles operated to wrap and to take the backing yarn only to pass the operating cam of the jacks of the plating needles.
3. In a knitting machine having independent needles, yarn guides for supplying wrapping, facing and backing yarns to said needles, cams for operating said needles to take said yarns, jacks for effecting selective operation of said needles for taking said yarns, jack selecting means for selecting jacks for determining the wrapping and plating needles and the needles which float both wrapping and plating yarns, cam means for operating the jacks of the wrap needles to effect operation of said needles and for raising the jacks of the needles which float both the wrapping and plating yarns, said jack selecting means positioning the jacks of the plating needles to pass said jack operating cam means, a cam for operating the jacks of the plating needles to effect operation of said needles and means positioning the jacks of the plating needles to engage the operating cam therefor and means positioning the jacks of the wrapping needles and the needles which float both the wrapping and plating yarns to pass the operating cam for the jacks of the plating needles.
4. In a knitting machine having independent needles, yarn guides for supplying wrapping, facing and backing yarns to said needles, cams for operating said needles to take said yarns, jacks for effecting selective operation of said needles by said cams, jack selecting means for selecting jacks for determining the needles for wrapping, plating and taking the backing yarn only, cam means for operating the jacks to effect operation of the wrapping needles and for raising the jacks of the needles which take the backing yarn only, said jack selecting means positioning the jacks of the plating needles to pass said jack operating cam means, a cam for operating the jacks of the plating needles to effect operation of said needles, means for positioning the jacks of the plating needles for engagement by their operating cam and means positioning the jacks of the wrapping needles and the needles taking the backing yarn only to pass the positioning and operating cams for the jacks of the plating needles.
5. In a knitting machine having independent needles, yarn guides supplying wrapping, facing and backing yarns to said needles, cams for operating said needles to take and knit said yarns to form plated fabric and embroidery and float stitch patterns, jacks for effecting selective operation of said needles in taking said yarns, means selecting for operation the jacks of needles taking the wrap and backing yarns to form embroidery and float stitch patterns, means for operating said selected jacks, means positioning the remaining jacks for operation while maintaining the selection made and a cam for operating said remaining jacks to effect a plating operation on their needles.
6. A circular knitting machine having independent needles, means for feeding wrapping, plating and backing yarns to said needles, independent jacks for determining the taking of said yarns by said needles, jack selecting means positioning said jacks for selective operation, cams raising the jacks of the wrap needles and the needles taking the backing yarn only, said jacks effecting operation of the wrap needles and said jack selecting means positioning the jacks of the plating needles to pass said jack operating cams, means returning the raised jacks to a position vertically displaced from the jacks of the plating needles, an operating cam for the jacks of the plating needles and means positioning the vertically displaced jacks to pass the operating cam of the jacks of the plating needles and the jacks of the plating needles to engage the operating cam therefor.
7. A circular knitting machine having independent needles, means for feeding wrap, back- 25 ing and plating yarns, in combination with independent jacks for raising said needles, selecting means for said jacks, cam means acting on selected jacks to cause needles to be raised for wrapping and to raise the jacks of needles taking the backing yarn only, a second cam means for acting on the remaining jacks to raise needles for plating and means shifting the first raised jacks to pass said second cam means and the remaining jacks to engage said second cam 30 means.
8. A circular knitting machine having independent needles, means for feeding wrap, back- 25 ing and plating yarns, in combination with independent jacks for raising said needles, selecting means for said jacks, cam means acting on selected jacks to cause needles to be raised for wrapping and to raise the jacks of needles taking the backing yarn only, means returning said raised jacks to a position vertically displaced from the remaining jacks, a second cam means 45 for acting on the remaining jacks to raise needles for plating and means for shifting the first raised jacks to pass said second cam means and the remaining jacks to engage said second cam means.
9. In a knitting machine having independent needles, yarn guides supplying wrapping, facing and backing yarns to said needles, cams operating said needles to take and knit said yarns, jacks positioning needles for operation by said 55 cams, means selecting jacks of needles for wrapping, plating and knitting patterns of the backing yarn only, cams operating the jacks of said wrapping and patterning needles, said jack selecting means positioning the jacks of said plating needles to clear the operating cams of the jacks of said wrapping and patterning needles, a cam to operate the jacks of said plating needles, means positioning the jacks of said wrapping and patterning needles to clear the operating cam for the jacks of said plating needles, and means positioning the jacks of the plating needles to engage their operating cam.
10. In a circular knitting machine having independent needles, yarn guides feeding wrapping, 70 facing and backing yarns to said needles, means selecting needles to knit an open embroidery pattern extending over a plurality of wales in a course and of a wrapping yarn and a backing yarn and plated fabric of the facing and back- 75

ing yarns between wales of said embroidery pattern, means selecting needles to knit patterns of the backing yarn only between wales of said embroidery pattern and means operating said 5 needles to take and knit said yarns, said facing and backing yarns being fed as weft yarns continuously around the needle circle.

11. In a circular knitting machine having independent needles, yarn guides supplying wrapping, facing and backing yarns to said needles, means for selecting needles to take and knit said facing and backing yarns as plated fabric, means to select needles to float said facing yarn and take and knit said backing yarn, means for selecting operating needles to take and knit said 10 backing yarn and a wrapping yarn to form an open embroidery pattern enclosing areas of plated fabric and fabric consisting of the backing yarn, said facing and backing yarns being 15 fed as weft yarns continuously around the circle of needles.

12. In a circular knitting machine having independent needles, yarn guides supplying wrapping, facing and backing yarns to said needles, means to operate said needles to take and knit said facing and backing yarns as a plated fabric, means selecting needles to float said facing yarn and to take and knit said wrapping yarn to form an open embroidery pattern enclosing 20 plated fabric and means to select needles to float said facing yarn within the limits of said embroidery pattern, said facing and backing 25

yarns being fed as weft yarns continuously around the circle of needles.

13. In a circular knitting machine having independent needles, yarn guides for supplying a wrapping yarn to a group of needles in a course and for supplying facing and backing yarns as weft yarns continuously around the circle of needles, cams for operating said needles to take and knit said yarns, jacks positioning needles for operation by said cams, and means selecting 10 jacks for positioning needles for operation to wrap, plate and knit patterns of the backing yarn comprising reader cams engaging said jacks and means operating said reader cams to make 15 all selections at one point.

14. In a circular knitting machine having independent needles, yarn guides for supplying a wrapping yarn to a group of needles in a course and for supplying plating and body yarns as weft yarns continuously around the circle of needles, cams operating said needles to take and knit said yarns, jacks positioning needles for selective operation by said cams, jack selecting means determining the selection of said yarns by said needles, said selecting means dividing said 20 jacks for operation of the jacks of wrapping and body yarn patterning needles in advance of the jacks of the plating needles, said jack selecting means positioning the jacks of the plating needles to preserve the selection thereof during the 25 operation of the jacks of the remaining needles.

IVAN W. GROTHEY.
